(57) **CLAIM**

The ornamental design for a mixer for viscous materials, as shown and described.

DESCRIPTION

FIG. 1 is a top perspective view of a mixer for viscous materials;

FIG. 2 is a front side view of the mixer;

FIG. 3 is a right side view of the mixer;

FIG. 4 is a rear view of the mixer;

FIG. 5 is a top view of the mixer; and,

FIG. 6 is a bottom view of the mixer.

The subject matter depicted in broken lines is not intended to be part of the claimed invention and is shown only for environment purposes.
